[57] CLAIM

The ornamental design for a automobile door knick protector, as shown and described.

DESCRIPTION

FIG. 1 is a front elevational view of the automobile door knick protector showing my new design;

FIG. 2 is a rear elevational view thereof;

FIG. 3 is a left side elevational view thereof;

FIG. 4 is a right side elevational view thereof;

FIG. 5 is a top plan view thereof;

FIG. 6 is a bottom plan view thereof; and,

FIG. 7 is a rear elevational view thereof, not fully extended, in position of use on an automobile which is fragmentarily shown in broken lines for illustrative purposes only and forms no part of the claimed design.

FIG. 1

FIG. 2

FIG. 3

FIG. 4
